UNITED STATES PATENT OFFICE

155,510

DESIGN FOR A HAIR TEST BOARD

Donald E. Hess, Seattle, Wash.

Application September 8, 1947, Serial No. 141,245

Term of patent 3½ years

(Cl. D52—1)

To all whom it may concern:

Be it known that I, Donald E. Hess, a citizen of the United States, residing at Seattle, county of King, Washington, have invented a new, original, and ornamental Design for a Hair Test Board, of which the following is a specification, reference being had to the accompanying drawing, forming a part thereof, in which

Fig. 1 is a perspective view of a hair test board, showing my new design.

Fig. 2 is a side elevation of the same on a reduced scale.

I claim:

The ornamental design for a hair test board, as shown.

DONALD E. HESS.
